UNITED STATES PATENT OFFICE.

EDWARD C. HOPPER, OF COVINGTON, KENTUCKY, AND CHARLES F. MCLEAN, OF CINCINNATI, OHIO.

TICKET RACK AND REGISTER.

SPECIFICATION forming part of Letters Patent No. 605,165, dated June 7, 1898.

Application filed June 26, 1897. Serial No. 642,370. (No model.)

To all whom it may concern:

Be it known that we, EDWARD C. HOPPER, a resident of Covington, in the county of Kenton and State of Kentucky, and CHARLES F. MCLEAN, a resident of Cincinnati, Hamilton county, and State of Ohio, citizens of the United States, have invented certain new and useful Improvements in Ticket Racks and Registers, of which the following is a specification.

The object of our invention is to provide a rack or board for holding different kinds of tickets, which tickets are consecutively numbered in blocks, are held on the board and sold therefrom at a predetermined time, with shutters to indicate the kinds of tickets for sale, which shutters may be thrown to conceal the name when no tickets of the kind named on the face of the shutter are for sale; also, peculiar means to shut off access to the board, while still exposing the tickets unsold, until account can be had of those sold by the superintendent or party in control. These objects are attained by the means illustrated in the accompanying drawings, in which—

Figure 1 is a front elevation of a ticketrack or board embodying our invention, the face of the board being accessible for the sale of tickets. Fig. 2 is a longitudinal vertical section of the same through line $x-x$ of Fig. 1. Fig. 3 is a detail view taken transversely through one of the guide- rods and looking down on top of the shutter.

Referring to the parts, A represents two upright boxes, between which the boards or racks B are supported.

B' is a cross strip or brace between the uprights A, upon which the rack B rests, and B² is a removable top which is held on the frames B by dowel-pins or other suitable connection for the purpose of holding the frames B in the unfolded position shown, the frames being hinged together, so that they may fold back to back and the removable top be placed between them for convenience in packing away or shipping.

To the inside of the uprights, near their forward corners, are secured guide- rods C, and to the upper and lower cross-pieces of the wire-screen frame D are secured U-shaped lugs or boxes d, within which are fitted fric-

tion-rolls d', which bear against the inside of the guide-rods and guide the frame in its upward or lower movement to expose the register-board, as shown in the drawings, or to close over the board when released. To the top of the frame are secured cords or wire ropes E, which pass over sheaves e, journaled in boxes secured to the tops of the standards A, and to which are attached weights E', which draw the screen up in front of the register-board when released.

To the cross-piece B' is secured a bracket f, upon which is mounted an electromagnet F. The armature f' is secured to or formed integral with the box d. The armature has an upwardly-extending angle-arm f'', the inwardly-projecting lug of which is perforated to receive the cord E, to which the counterpoised weights E' are connected.

When the screen D is drawn down and the circuit closed through wires 1 and 2, the armature will be held to the magnet, keeping the screen in the open position shown. After the sale of tickets is closed the electric circuit is opened by the superintendent or other party in charge from any point to which the wires 1 and 2 may pass, and the weights will throw the screen to the closed position, in which position the spring-loop a will engage in the box d and hold the screen in the closed position until a record of the tickets sold is made. a' are stud-plates secured to the guide-rods C and to the uprights A to steady the rods in position.

To the face of the ticket-boards B B are secured any desired number of clips G. These are formed, preferably, of light sheet steel, brass, or other spring metal, and in cross-section are semicylindrical or arched over flat flanges g, by which the clips are fixed upon the board, thus allowing the cylindrical or arched portion to be swung outwardly by pressing upon the lugs or thumb-pieces g' to receive a block of tickets H, which tickets are numbered from "00" to "99," inclusive. Upon the front of the flange g are secured plates J, which have overturned flanged edges, under which cards j, descriptive of the tickets held by the clips, are placed. To the upper edges of the clip-flanges g are hinged shutters K, carrying upon their faces the num-

ber of the clips, which numbers are exposed to view when the shutters are thrown up and held by spring-catches *k*. When no tickets of the kind indicated by the cards *j* are for sale, the shutters are thrown down over the cards *j*, concealing the name of the ticket, as shown by the clips numbered 2 and 9 on both boards. Ordinarily there are one hundred tickets of each kind held by the clips, and if any block is sold out before time for closing the shutter over the frame the number "100" is placed over the lug *g'*, as indicated at clip No. 6 on the right-hand board, and a new block placed in the clip. As shown by this clip, one hundred and three of the No. 6 tickets have been sold. At a predetermined time for closing the sale the switch opening the electric circuit is operated, the screen drawn by the weights up over the board and held in the closed position until the accountant or other proper officer makes a register of the number of each kind of tickets sold, which must correspond with the price of each ticket if the vendor or clerk makes correct return of the cash received from the sales, and, if not, the accountant can readily detect the fraud or mistake, if one has occurred, by counting the remaining tickets held in the clips.

It is obvious that instead of the electromagnet for holding and releasing the screen a lock could be employed, the key of which is held by the accounting officer, or that many other tripping or releasing devices may be employed instead of the one shown, and it is also obvious that different forms of clips for holding the tickets may be employed without departing from the spirit or scope of our invention.

We have shown our board of two parts, each side having the same number of clips and ticket holding and registering arrangements. The purpose of this arrangement is to provide for holding first and second class tickets of the same kind; but it is obvious that instead of having the two boards numbered the same the whole may be numbered consecutively, so that only one class of tick-

ets is sold. In this case we may provide two devices similar to that shown, one for the first-class and the other for the second-class tickets.

What we claim is—

1. In a ticket and registering rack the combination of the board, the ticket-clips secured thereon, the name-plate holders above each clip, and the hinged shutters having numerals to indicate the number of the clip when thrown up and closed over the plate when no tickets are held by the clip, substantially as shown and described. 55

2. The combination of the boards having each consecutively-numbered ticket-clips secured thereon, the swinging member of the clip having a lug projecting therefrom to open the clip and form a hook to suspend the last ticket and block when a new block of tickets is to be inserted, the name-plate holders above said clips, and the hinged shutters having numbers on their faces corresponding to the number of the clip when thrown up, but adapted to be thrown down over the name-plate holders when no tickets of the kind or class are for sale. 65

3. The combination of the uprights, the cross-piece bracing the uprights in position, the board between the uprights above said cross-piece, the ticket-clips secured upon said board, the guide-rods secured to said uprights, the screen fitted to slide between said guide-rods to cover or uncover the board, the fixed electromagnet, the armature secured to the screen-frame to hold it in its lower position, the sheaves in the top of said uprights, cords secured to the screen and passing over the sheaves, weights to overbalance the weight of the frame and carry it to its upper position in front of the board, and catches to retain it in the upper position, substantially as shown and described. 70
